UNITED STATES PATENT OFFICE

JOSEPH B. HARRIMAN, OF NORTH READING, MASSACHUSETTS

POULTRY LIGHT CONTROL

Application filed February 11, 1927. Serial No. 167,546.

For increasing winter egg production, it is customary among many poultrymen to illuminate the hen house for a short time in the evenings, or early mornings, or both, to enable the hens to bestir themselves and fill their crops at such times, and thereby to shorten the lengths of their fasts during the long, cold nights.

An early morning use of lights is a quite usual method; a very frequent practice therefore being to arrange an alarm clock to throw on the lights a few hours before daylight; the poultryman switching them off after daylight. While this has the advantage of simplicity, the use of lights in the evening is superior in several respects, among which is the fact that it gives the birds a heavy feed of grain the last thing at night and better enables them to withstand the cold. An evening lunch system is also much less expensive, inasmuch as it requires but an hour or even less of current consumption, instead of the two or three of morning illumination.

The difficulty in evening illumination is that, if the lights are thrown off while the birds are feeding, they have great difficulty in again finding their roosts in the dark; making it necessary to provide some method of dimming the lights.

The object of this invention is the construction of automatic means whereby, after the lighting current has been switched on, and sufficient time has elapsed for proper feeding, a resistance will be cut into the circuit to partially dim the lights, so that a majority of the hens will seek their roosts; then, after a suitable interval, the lights will be still further dimmed one or more times as a hint to the remaining feeders; and after another short interval, the current will be wholly shut off and the coop left in darkness.

With his poultry house thus equipped, the poultryman needs only to go out to the house after supper at a suitable hour, say seven or eight o'clock; throw a switch to turn on the lights; scatter grain for the evening lunch; glance about to see that all is well, and then return to his fireside knowing that the illumination will be dimmed and finally shut

off without further effort or thought upon his part.

In the drawings forming part of this specification, Fig. 1 is a plan view, partially in section, illustrating a poultry light control embodying my invention. Fig. 2 is a side sectional view of the same. Fig. 3 is a view from beneath of the clockwork and part of the associated mechanism. Fig. 4 is a similar view at another period of its operation.

The main features of the light control consist of a rheostat; clockwork; means operated by the latter for switching into the lighting circuit different degrees of the rheostat resistance, and for cutting out all current therefrom; and means for starting the action of the clockwork when the current is switched on, and for stopping the motion of the clockwork at the time the current is switched off.

The rheostat embraces a resistance 1 of well known construction having several taps 2, and supported upon a suitable base 3 adapted to be screwed to a wall or shelf. The clockwork 4, of sturdy construction but needing not to be of an expensive form for accurate timekeeping, is attached to the under surface of the cover 5 of a box 6, which is preferably cast as a part of the base 3, though having a bottom 8 of insulating material. In place of hands, a cam disk 7 is attached to the arbor 9 which makes a complete revolution once an hour. This disk is peripherally stepped, and receives the pressure of a lug 10 carried by an arm 11 rigid with the lower end of a spindle 12. The latter rises through the cover 5 and is provided with an operating handle 12 whose swing is limited at one end by a stop post 14, as shown in Fig. 2.

Near the bottom of the box 6 is pivotally supported a second arm 15 provided with a spring 16 for pressing it toward one limit of its swing, as the stop 17, and is adapted to swing past and in touch with the contacts 19, 20, 21; the arms 11 and 15 being made to move synchronously by means of a pin 22 projecting from the arm 11 into a hole in the insulation 23 of the arm 15.

The arm 15 is kept in circuit with a wire 24 by means of a leaf spring 25 pressing thereon throughout its play, as indicated in Fig. 1.

The two contacts 19, 20 are wired through an insulated cable 26 to the terminals 28 and 29 of a double plug 27; these terminals being adapted to be inserted into any adjacent pair 5 of the socket-holes 30, and are so shaped as to prevent the double plug from being turned about and inserted wrongly into the sockets. I do not restrict myself to two dimmings only, as the number of contacts can be readily 10 increased, and the stages of dimming in accordance.

The contact finger 31 of each socket hole 30 is wired to one of the taps 2 of the resistance unit 1; the terminal tap 32 being wired to the 15 contact 21, which in turn is connected with the wire 33.

Consequently, when through the action of the handle 13, the arm 15 is swung into engagement with the contact 21, current passes 20 directly from the switchboard 34 through the wire 24, leaf spring 25, arm 15, contact 21, wire 33 and the lighting units 35 back to its source, thereby giving to the bulbs full current. At the same time, the spring wire 36 25 which is carried by the arm 11 into engagement with the balance wheel 37, thereby holds the clockwork motionless, so long as the position of the arm was such as to cut out the lighting current, sets the balance wheel into 30 oscillation and thereby starts the clockwork into action as the arm 15 is swung over to the contact 21.

When the clockwork has slowly moved the arm 15 from the contact 21 to the contact 20, 35 and the plug terminals 28, 29 have been inserted in some pair of the holes 30, the current is forced to pass through more or less of the resistance 1 and to be correspondingly reduced, thereby dimming the lights accordingly. After a few minutes of this dim light, 40 the clockwork swings the arm 15 to the contact 19, cutting in more resistance, and still further dimming the light; which operation is repeated if more than these two degrees 45 of dimming are desired. Then, following the last dimming period, the arm 15 is moved to its limit 17, thereby switching out all current and leaving the hen house wholly in the dark.

The purpose of the many socket holes 30 is 50 to adapt the light-control to different sources and voltages of current, and to different amounts of lighting used in the poultry plant. The lesser the resistance desired, as for greater amounts of lighting, the nearer the 55 plug terminals 28, 29 are to be located to the tap 32. From the latter, the current passes through a wire 39 to the contact 21, and thence to the wire 33.

The clockwork 4, in addition to main- 60 spring 38 and the usual train, embraces a balance wheel 37, an arbor 9 and a cam disk 7 which is peripherally stepped, as shown in Figs. 3 and 4. When the lug 10 of the arm 11 rests against the periphery of the cam disk 7, the clockwork at once begins to run, its

start being rendered positive by the action of the spring wire 36 on the balance wheel as it is swung away therefrom. During about forty minutes of the rotation of the cam disk 7, the arm 11 holds the arm 15 in touch with the contact 21, and hence full illumination 70 of the poultry house is maintained.

Inasmuch as Figs. 3 and 4 show the clock-work as upside down, the arm 11 appears to be in the position which would hold the arm 15 at the opposite limit from the contact 21, whereas the reverse is the actual fact. 75

At the termination of the forty minute period, the shoulder 41 passes the lug 10 and the arm 11 swings inward until stopped by the step 42, thereby bringing the arm 15 into touch with the contact 20 and giving the first dimming to the lights. At the end of a period of about ten minutes, the shoulder 43 passes the lug 10 and the arm 11 swings inward again to the step 44, and so presents the arm 15 into touch with the contact 19; thus further dimming the light, which process is repeated if there are more than two stages of dimming. At the end of a final period, the lug 10 is passed by the shoulder 45 and swings into the deep slot 46, thereby carrying the arm 15 to its limiting stop 17, and cutting all current from the bulbs 35. 80 85 90

When the arm 11 makes this last movement, the spring wire 36 is put into engagement with the balance wheel 37, and the clock ceases further action. 95

Upon the approach of night, when it is desired to give the poultry an evening lunch, 100 the poultryman swings the handle 13 over to the stop 14, and thereby moves the arms 11 and 15 to the position for full illumination; the lug 10 being chamfered and both the portion 47 and the arm 11 being resilient 105 to permit the movement. When the lug 10 passes the finger 47 and is held by the periphery of the disk 7, and the spring wire 36 having started the clockwork into operation, full current is switched to the bulbs 35 and 110 the hen house remains fully illuminated for the period permitted by the disk 7, as above described.

By having the clockwork run only an hour a day, instead of a full twenty-four hours, it 115 becomes unnecessary to wind it more frequently than every three weeks or so. This not only saves the time required for winding, as well as the wear of the clock, but reduces proportionately the chances of forgetting to wind it, with the consequent failure of the clock to shut off the light. 120

The base 3 is preferably formed with vertical side pieces 50 each provided with a recess open above, down into which the resistance element 1 can be slid and suitably supported. 125

What I claim as my invention is:

1. In a current control, the combination of a switch-arm, a plurality of circuit contacts, 130

a resistance having different sections thereof in circuit with said contacts, yielding means urging said arm into engagement with said contacts, and clockwork acting to restrain 5 said arm from said engagements, the clockwork having a plurality of timed restraints, whereby different degrees of resistance are successively cut into the circuit.

2. In a current control, the combination of 10 a switch arm, a plurality of circuit contacts cooperating therewith, a resistance having different sections in circuit with said contacts, yielding means urging said arm into engagement with said contacts, a clock having a cam 15 disk mounted on the arbor of its minute hand, said cam having a plurality of steps in the periphery, and means bearing against said periphery restraining said arm from said engagements.

20 3. In a current control, the combination of a switch arm, a contact co-operating therewith and directly connected with one pole of the circuit, a resistance connected with one pole of the circuit, a second contact connected 25 with said resistance and also co-operating with said arm, yielding means urging said arm into engagement with said contacts, and a clock adapted for restraining said arm from said engagements at different periods, said 30 arm being connected with the other pole of said circuit.

4. A current control comprising a resistance element having several taps, contact connected with a tap at one end and also with 35 one pole of the circuit, a switch arm co-operating with said contact, a plurality of other contacts co-operating with said arm and adapted to be variously connected with the others of said taps, said arm being connected 40 with the other pole of said circuit, and adapted to co-operate with all of said contacts, and time-controlled means for moving said arm from the first contact to each of the others in successive periods of time.

45 5. The combination of a rheostat including a resistor, a circuit-controller having a plurality of fixed contact members connected with different sections of said resistor, a switch arm movable over said contact members in succession, means biasing said switch 50 arm for movement over said contact members from a circuit-closed position to a circuit-opening position, manual means for moving said switch arm in the opposite direction 55 against said biasing means, and time-controlled mechanism having means to control the movement of said switch arm under operation of said biasing means, said switch arm being movable manually free from control 60 of said time-controlled mechanism.

6. The combination of a rheostat including a resistor, a circuit-controller having a plurality of fixed contact members connected with different sections of said resistor, a 65 switch arm movable over said contact mem-

bers in succession, means biasing said switch arm for movement over said contact members from a circuit-closed position to a circuit-opening position, manual means for moving said switch arm in the opposite direction against said biasing means, and time-controlled mechanism having means to control the movement of said switch arm under operation of said biasing means, said switch arm being movable manually free from control 70 of said time-controlled mechanism, said time-controlled mechanism also including means to permit a rapid movement of said switch arm when interrupting the circuit at 75 said fixed contact members.

7. The combination of a rheostat including a sectional resistor, a circuit-controller having a plurality of fixed contact members, a switch arm movable over said contact members in succession, switching means arranged 80 to connect some of said contact members at will with selected ones of a larger number of sections of said resistor, means biasing said switch arm for movement over said contact members from a circuit-closing position to a 85 circuit-opening position, manual means for moving said switch arm in the opposite direction against said biasing means, and time-controlled mechanism having means for controlling the movement of said switch arm 90 under action of said biasing means.

8. The combination of a circuit-controller having a movable controller-arm, means biasing said arm for movement in a circuit-opening direction, manual means to move 100 said arm in a circuit-closing direction against said biasing means, time-controlled mechanism having means to delay the circuit-opening movement of said arm including a movable time-controlled member having a recess therein in which said arm is held by said biasing means in the circuit-opening position of said arm, and means to hold said arm from immediately re-entering said recess after it 105 has been moved manually out thereof at least until said member has moved the entrance of said recess away from said arm.

In testimony that I claim the foregoing invention, I have hereunto set my hand this 5th day of February, 1927.

JOSEPH B. HARRIMAN.
